DISPLAY BOARD

Sidney R. Wirth, River Forest, Ill., assignor to
 Advertising Metal Display Co., Chicago, Ill., a
 corporation of Illinois

Application September 11, 1948, Serial No. 48,793

1 Claim. (Cl. 211—87)

1

This invention relates to improvements in display boards and it consists of the matters herein-after described and more particularly pointed out in the appended claim.

The boards with which the present invention is more especially concerned includes a supporting panel and members that project forwardly from the bottom of the board for the hanging support of the articles displayed on the board. A display board of this general type is illustrated and described in Patent 1,998,243 of April 16, 1935, to Herbert H. Krueger.

One of the objects of the present invention is to provide an improved structure for attaching the article supporting hangers to the panel of the board and this in a manner whereby the hangers are better able to withstand the load of the articles supported and will not so easily loosen up from the panel.

A further object of the invention is to so form the panel with a part which not only stiffens the same better to resist warping, but which part also is employed for engagement by portions of the hangers to resist the tendency of the hangers to tip under the weight of the articles supported thereby.

The above mentioned objects of the invention, together with others, as well as the several advantages thereof, will more fully appear as the specification proceeds.

In the drawing:

Fig. 1 is a perspective view of a display board embodying the preferred form of the invention, as viewed from the front thereof.

Fig. 2 is a view in rear elevation of the display board appearing in Fig. 1, but on a scale slightly enlarged over that of Fig. 1.

Fig. 3 is a detail horizontal sectional view through a part of the improved display board as taken on the line 3—3 and on a scale enlarged over that of Fig. 2.

Fig. 4 is a fragmentary detail perspective of parts of the board as viewed from the back thereof, on substantially the scale of Fig. 3.

Fig. 5 is a view similar to and substantially on the scale of Fig. 4 and shows a modified arrangement for securing the hangers to the panel of the board, and which will be more fully referred to later.

Referring now in detail to that embodiment of the invention illustrated in Figs. 1 to 4 inclusive, the improved board includes the sheet metal panel or front 10, which is of a horizontally elongated rectangular shape and is provided along the top and sides thereof with rearwardly extend-

2

ing flanges 11 and 12 respectively and is further provided at the bottom with a rearwardly extending ledge 13 of the same depth as said flanges. The rear margin of said ledge is turned back upon but is spaced above the remainder of said ledge to form a forwardly facing flange 14, which not only stiffens the ledge but also defines a forwardly opening groove or channel 15 along the back margin of the ledge. The panel is provided along its bottom with pairs of longitudinally spaced openings 16, the bottoms of which are substantially flush with the top of the ledge, as best appears in Fig. 4.

Associated with said panel thus far described is a plurality of hangers, one for association with each pair of openings 16 and indicated as a whole by the numeral 17. Each hanger is made of a length of wire bent into substantially a U-shape so as to include a pair of laterally spaced side legs 18—18 each of which is turned upwardly at its front free end as a hook 19, the other end of said legs being operatively connected together by a cross member 20. This member spaces the legs apart a distance corresponding to the distance between the openings 16 of each pair. The wire from which the hangers are made is of such a diameter as to readily pass through the openings, as well as to permit entry of the cross bar 20 into the groove 15 from the open front thereof.

On the back of the panel and disposed in a vertical plane between the axes of the opening 16 of each pair is pivotally mounted a hanger confining member 21, which includes a pair of side flanges 22 and a web 23. The flanges 22—22 have a depth approximating the distance between the front edge of the flange 14 and the back of the panel. The member 21 is somewhat elongated and it is pivoted to the panel for swinging movement by means of a rivet 24 that passes through the top end of the web and the panel, centrally between the openings 16 of each pair.

To apply a hanger to the panel, the procedure is as follows: The associated hanger confining member 21 is swung into a substantially horizontal position, such as appears at the left hand side of Fig. 1, and wherein its bottom end is spaced above the ledge 13. A hanger 17 is then taken in hand and from the rear of the panel the hooks 19—19 are passed through the associated pair of openings 16, while the hanger is disposed at an angle extending upwardly and rearwardly from the junction of the panel and its ledge 13. The hanger is then moved forwardly and downwardly until the cross bar 20 thereof engages the ledge 13 forwardly of the flange 14. Thereafter the

hanger is moved rearwardly so that the cross bar 20 thereof enters the groove 15 under the flange 14 at the rear of the ledge and at which time the legs 18-18 are disposed in a plane parallel with the ledge and with the rear end of said legs engaging on said ledge. Thereafter the associated hanger confining member 21 is swung downwardly to extend in an upright position (as at the right hand side of Fig. 4), at which time the flanges 22-22 close the open front of the channel 15 to 10 confine the hanger in place against any forward movement.

It is to be noted that those portions of legs 18 forwardly of the panel are longer than those portions to the rear thereof. When the articles to be displayed are hingingly engaged upon the longer front portions of the legs, the legs function as a lever tending to fulcrum about that part thereof disposed in the associated opening. This action, however, is resisted by the engagement of the cross bar 20 of each hanger, under the flange 14 and which acts as a "hold down" action thereon. Thus the member 21, in this instance, is not relied upon to prevent the swinging movement of cross bar 20 but merely to prevent the hangers from moving forwardly by blocking the open front of the channel and thereby confining the cross bar therein.

In the structure thus far described, the cross bar 20 of the hangers is straight and without bends or bows therein. However in Fig. 5, the cross bar 20 is illustrated as having a centrally arranged bowed portion 20a, which when the end portions of said bar are disposed in the channel, projects forwardly to a point beyond the front edge of the flange 14. With such a structure, a slightly modified form of hanger confining member 21a is employed, which includes a web 22a and front and rear flanges 23a-23a with the rear flange pivotally mounted on the panel by a rivet 24a. The web 22a is of such a width that when the member 21a stands in the upright operative position, as in Fig. 5, the front flange 23a

engages the central bowed portion 20a of the cross bar and confines the hanger in place.

With the construction described, by the provision of the turned over flange 14, the ledge 13 is materially stiffened against warping and this flange also acts to hold down the rear end of the hangers upon the ledge, the members 21 merely blocking the open front of the groove and in no way having a hold down function so far as the cross bar of the hangers is concerned.

While in describing the invention I have referred in detail to the form, construction and arrangement of the parts involved, the same is to be considered only in the illustrative sense and therefore I do not wish to be limited thereto, except as may be specifically set forth in the appended claim.

I claim as my invention:

A display board embodying therein a panel having a pair of laterally spaced openings therein, a ledge projecting rearwardly from said panel below said openings, hook-like means carried by said ledge and facing toward said panel, a hanger comprising laterally spaced legs and a member connecting the rear ends of said legs, with said legs inserted through said openings and said connecting member being engaged under said hook-like means, and including a portion bowed forwardly, and means engageable with said bowed portion for confining said connecting member in position under said hook-like means.

SIDNEY R. WIRTH.
